MORTAR APPLICATOR HAVING A FLEXIBLE
DISPENSING TUBE

Earle N. Floyd, Mississippi City, Miss.

Application May 27, 1949, Serial No. 95,762

2 Claims. (Cl. 222—210)

1

This invention relates to means for applying and spreading mortar, cement and the like, and particularly to a mortar applicator.

The main object of my invention is to provide special manually-operated and directed means for applying and/or spreading mortar and cement when erecting masonry, and to minimize the amount of human effort and mortar material required therefor.

Another object is to provide a manually-held mortar applicator of the indicated character with means for holding a predetermined amount of mortar and for controlling flow of mortar therefrom at will.

A further object is to have such a mortar applicator provided with means for urging the mortar to flow therefrom with virtually a feeding action.

It is also an object to have a mortar applicator as outlined which is capable of being partly folded up to reduce over-all length for portability and also prevent injury to the control valve or gate of the device.

Other objects and advantages of the invention will appear in further detail as the specification proceeds.

In order to facilitate ready comprehension of this invention for a proper appreciation of the salient features thereof, the invention is illustrated on the accompanying drawing forming part hereof, and in which:

Figure 1 is a side elevation of a mortar applicator, with parts broken away, made according to my invention and embodying the same in a practical form, the full line showing of the spout indicating its position for discharge of the contents and the dotted line showing of the spout indicating its position when the device is being transported from one place to another;

Figure 2 is a vertical section of the intermediate flexible portion of the device of Figure 1, with parts broken away and shown on an enlarged scale with the portions to which it is attached at the upper and lower ends thereof;

Figure 3 is another enlarged elevation of the lower portion of the device of Figure 1, as seen from the right in that figure;

Figure 4 is a reduced elevation of the lower portion of the device of Figure 1 showing the flexible tube bent upwardly with handle portion of the operating lever extending through the hook.

In the views the same reference numerals indicate the same or like parts.

In the building art, and particularly referring to the erection of masonry, it is usual to provide supplies of mortar in piles upon mortar boards

2

accessible to the masons erecting a wall, so that trowel portions of the mortar are taken from time to time from the mortar thus applied by the masons at the wall.

It is the ancient and generally current practice for the mason to apply the mortar in trowel quantities to the masonry under construction, necessitating for each such trowel application his walking to the nearest placed mortar board for his supply, and then as often returning to that part of the wall under construction to deposit the same. The device herewith submitted attempts to eliminate this constant duplication of effort by placing in the hands of the mason or operator an amount of mortar easily carried and disposed of in construction. However the arrangements may be, it appears unavoidable that at least one-fourth of the mortar is wasted in the process of laying the mortar or spreading it for laying bricks, blocks or other building elements therein. On the other hand, when hollow tiles are used of various dimensions the wall thicknesses of such units vary and greatly increase the labor in spreading the mortar on the thin walls thereof, and in fact the increase of wastage of mortar is so great that practically two-thirds is wasted by falling at the sides, or even inside the hollow portions of such tiles, so that not only the materials of which the mortar is composed, but the time and labor consumed in producing it are largely wasted.

Upon considering this problem, it has occurred to me that means should be available for spreading mortar in a far more economical and convenient manner to save labor, time and mortar when spreading the latter.

As a result, I have succeeded in producing a special device for applying mortar to bricks, building blocks, tiles and the like, as will now be more fully set forth.

Hence, in the practice of my invention, and referring again to the drawing, a manually-held hopper 4, which is open at the top, is substantially frusto-conical with the smaller end directed downward, and is provided with a bail 5 pivotally connected by rivets or short bolts 6 to the opposite sides of hopper 4 at the upper end thereof. Below the upper open end 7 upon one side intermediate the sides to which the bail is attached is secured a hand grip 8 by means of rivets 9, 9 or the like, while upon the same side a distance downwardly from the hand grip is fixed a horizontally-disposed hook 10 for a purpose which will presently be described. At the lower end 11 of hopper 4 is a short

downward cylindrical continuation 12 terminating in an external bead 13 serving as a stop for a hollow cylindrical flexible and more or less elastic operating diaphragm or tube 14 depending from the exterior of cylindrical portion 12 and secured upon the same by means of a clamping strap 15 secured together at the ends 16 thereof by means of a screw or bolt 17. As the operating diaphragm 14 is secured to the lower cylindrical extension 12 above the external bead 13 thereof, the latter prevents the upper end 18 from slipping off the mentioned cylindrical lower portion of the hopper.

The depending hollow cylindrical diaphragm 14 may be made of fabric, flexible plastic, natural or artificial rubber, such as Koroseal or neoprene, and the like, so that it will be not merely flexible, but more or less elastic in addition. The lower end 19 of hollow diaphragm 14 is clamped upon the upper hollow cylindrical end 20 of a dispensing spout 21 by means of a second clamping strap 22 immediately beneath the upper external bead 23 on the spout, the ends 24 of the strap being retained together by a screw or bolt 25, so that the spout 21 is prevented from slipping out from within the lower end 19 of the mentioned cylindrical diaphragm 14. The upper end 26 of the spout member 21 is larger than the lower end 27, the spout member being substantially frusto-conical with the lower end cut obliquely to form a delivery opening. Upon the intermediate portion of one side of the delivery spout 21 a gate valve 31 is mounted for rocking movement about an axis or pivot member 29, which is transverse of the spout, into and out of bridging relation with respect to the lower end 27 of the spout 21. Specifically, on one side of the delivery spout 21 are mounted a pair of lugs 28, 28 through which extends a pivot member 29 upon which is pivotally mounted a lever 30 integral with a delivery valve or gate member 31 which is substantially rectangular and disposed at an angle to lever 30, while upon the upper end of the latter is formed a handle 32 by which to pivot lever 30 about pivot member 29 in order to open or close the lower delivery opening 33 at the lower end 27 of the delivery spout 21. In order to bias the disc-shaped gate or closure member 31 against the lower end 27 of spout 21 to close the lower opening 33 thereof, a spring 34 is disposed in contact with lever 30 in a position to engage with pivot member 29 and with the external wall of dispensing spout 21 within lever 30, such spring being capable of assuming various forms to perform this function. A handle 38 is secured to the spout 21 and is located between the spout and the lever 32. The handle 38 is curved inwardly toward the spout 21, as at 39, and the lever 32 is curved outwardly in a reverse direction, as at 40. Thus the handle 38 and the lever 32 provide a more comfortable and secure grasp on or support for the spout 21, this affording greater ease of operation of the lever 32 and the gate valve 31. For example, the operator may grasp the curved part of the lever 32 with four fingers and insert his thumb under the curved part 39 while manipulating the gate valve 31 by merely bringing the lever 32 closer to the handle 38.

When the device is to be used by a mason or other artisan, mortar is introduced into the upper open end 7 of hopper 4, while the hopper is held by hand and the lower spout member 21 given a slight circular motion about a vertical

axis so as to flex the hollow diaphragm 14 in various directions, so that the mortar will descend to the bottom of the spout and fill the diaphragm, and at least partly fill the hopper as well. Then, when the requisite amount of mortar has been introduced, the spout 21 is bent upwardly into the position indicated in Figure 4 and the free handle portion 32 of the operating lever 30 introduced from above within the hook 10, when the diaphragm 14 will be folded upwardly and the entire device will be sufficiently reduced in vertical length to allow the same to be carried readily without dragging the spout 21 or causing the valve or gate closure 31 thereof to make accidental contact with any objects and perhaps be damaged thereby. The bail 5 serves to carry the device to the point at which it is to be used. Of course, if desired, handle 32 may be provided with a hook to engage the hook 10, or the latter may be modified to form a pair of opposed hooks or springs adapted to engage with handle 32, if desired, the main point being that hook 10 serves in some manner to hold handle 32 and thereby retain dispensing spout 21 in raised position while the device is carried to the point of use.

When the present applicator is to be used, handle portion 32 of the operating lever 30 is first disengaged from hook 10 so that dispensing spout 21 extends downwardly, as indicated in full lines in Figure 1, the bail 5 being held in the hand or supported on forearm and spout 21 being held in close proximity to the work surface upon which the mortar is to be deposited, when the other hand is used to grip the spout and give the same a twisting or circular movement with the fingers pressing handle portion 32 to open valve 31, when it will be found that mortar will issue and be laid upon the brick work or other surface to be covered with the mortar, as long as valve member 31 remains open. The twisting movement given to the spout will cause flexure of hollow diaphragm 14 in various directions and produce a downward feeding movement of the mortar which is readily controlled by the amount of movement imparted to the spout, as well as the degree of opening of valve member 31 provided by pressure upon handle portion 32 toward the spout. Due to the fact that the mortar is largely protected from the air and also, as it were, constantly kneaded and kept in motion by the circular twisting movement given to the spout and actually imparted to the mortar by the flexing movements of diaphragm 14, the mortar is prevented from setting, and remains in a plastic condition until actually applied, and thus, also, readily flows in well-regulated manner from the lower opening 33 of spout 21, as regulated by the valve 31. The rectangularly shaped gate valve 31 may be manipulated in such a manner as to give a troweling or spreading action to any excessive amount of mortar that might have escaped from the spout 21. This troweling action is brought about by simply lowering the edge of the gate valve 31 so that the same may be drawn along and in contact with the excessive mortar.

Manifestly, variations may be resorted to and parts and features may be modified or used without others within the scope of the appended claims.

Having now fully described my invention, I claim:

1. A portable mortar applicator comprising an upstanding rigid hopper having a cylindrical por-

tion on the lower end, a bead surrounding said portion adjacent the free end of the latter, means on the upper end of said hopper for dependingly supporting the same from a hand of a user, a hook projecting exteriorly of said hopper above and spaced from the lower end thereof, a tube fabricated of flexible material positioned below said hopper and having the portion adjacent one end surroundingly engaging said bead and embracingly secured to the cylindrical portion of said hopper, a rigid spout positioned below and having one end in alignment with the other end of said tube, a second bead surrounding said spout adjacent said one end thereof, the portion adjacent said one end of said spout extending into the other end of said tube, means surrounding a portion of said tube below said spout bead and embracingly secured to said tube, said tube being bendable intermediate its ends to thereby permit the shifting of the spout and the lower end portion of said tube from its depending position with respect to said hopper to an elevated position with respect to the latter, a lever arranged exteriorly and longitudinally of said spout and on the same side of said hook and having on the lower end a gate member bridging the other end of said spout, said lever being mounted on said spout intermediate its ends for rocking movement about an axis transverse of said spout to thereby shift the gate member into and out of bridging relation with respect to the other end of said spout, and a handle projecting from the upper end of said lever for effecting the rocking movement of the latter, said handle being supported in said hook when said spout and lower end portion of said flexible tube have been shifted to the elevated position with respect to said hopper.

2. A portable mortar applicator comprising an upstanding rigid hopper having a cylindrical portion on the lower end, a bead surrounding said portion adjacent the free end of the latter, means on the upper end of said hopper for dependingly supporting the same from a hand of a user, a tube fabricated of flexible material positioned below said hopper and having the portion adjacent

5 one end surroundingly engaging said bead, a strap positioned exteriorly of and embracing the portion of said tube adjacent said one end above said bead for securing said tube to said hopper, a rigid spout positioned below and having one end in alignment with the other end of said tube, a second bead surrounding said spout adjacent said one end thereof, the portion adjacent said one end of said spout extending into the other end of said tube, a second clamping strap positioned exteriorly of the portion of said tube below said spout bead and embracingly secured to said tube for securing said spout to said tube, a hook projecting exteriorly of said hopper above and spaced from the lower end thereof, said tube being bendable intermediate its ends to thereby permit the shifting of the spout and the lower end portion of said tube from its depending position with respect to said hopper to an elevated position with respect to the latter, a lever arranged exteriorly and longitudinally of said spout and on the same side of said hook and having on the lower end a gate member bridging the other end of said spout, said lever being mounted on said spout intermediate its ends for rocking movement about an axis transverse of said spout to thereby shift the gate member into and out of bridging relation with respect to the other end of said spout, and a handle projecting from the upper end of said lever for effecting the rocking movement of the latter, said handle being supported in said hook when said spout and lower end portion of said flexible tube have been shifted to the elevated position with respect to said hopper.
